UNITED STATES PATENT OFFICE.

PHILIP H. OBER, OF MANSFIELD, OHIO, ASSIGNOR TO THE MANSFIELD TIRE & RUBBER CO., OF MANSFIELD, OHIO.

DESIGN FOR AN AUTOMOBILE TIRE.

Application filed June 15, 1926. Serial No. 18,060. Term of patent 7 years.

To all whom it may concern:

Be it known that I, PHILIP H. OBER, a citizen of the United States, residing at 40 Stewart Ave., Mansfield, in the county of Richland and State of Ohio, have invented a new, original, and ornamental Design for Automobile Tires, of which the following is a specification, reference being had to the accompanying drawing, forming part thereof.

Figure 1 is a perspective view of an automobile tire or casing, showing my new design, and Figure 2 is a plan view of a portion of a tire.

I claim:

The ornamental design for an automobile tire, as shown.

PHILIP H. OBER.
